CLAIM

The ornamental design for a luminaire, as shown and described.

DESCRIPTION

FIG. 1 is a perspective view of a luminaire in accordance with the design;

FIG. 2 is a top plan view thereof;

FIG. 3 is a bottom plan view thereof;

FIG. 4 is a front elevation view thereof, with the rear elevation view being a mirror image of the front elevation view; and,

FIG. 5 is a left side elevation view thereof, with the right side elevation view being a mirror image of the left side elevation view.

The broken lines shown on the drawings depict portions of the luminaire that form no part of the claimed design.
